PORTABLE FOUNTAIN

Anthony C. Mifsud, West Hempstead, N. Y.

Application July 7, 1950, Serial No. 10,993

Term of patent 7 years

(Cl. D91—4)

To all whom it may concern:

Be it known that I, Anthony C. Mifsud, a citizen of the United States, residing at West Hempstead, county of Nassau, State of New York, have invented a new, original, and ornamental Design for a Portable Fountain, of which the following is a specification, reference being had to the accompanying drawing, forming a part of this application.

In the drawing,

Fig. 1 is a perspective view of a portable fountain, showing my new design;

Fig. 2 is a top plan view of the fountain; and
Fig. 3 is a side elevational view of the fountain.

I claim:

The ornamental design for a portable fountain, as shown.

ANTHONY C. MIFSUD.
